William A. Evers Inventor

Watson E. Coleman Attorney

UNITED STATES PATENT OFFICE.

WILLIAM A. EVERSON, OF MARTINSBURG, WEST VIRGINIA.

RAIL JOINT.

Application filed June 16, 1925. Serial No. 37,545.

To all whom it may concern:

Be it known that I, WILLIAM A. EVERSON, a citizen of the United States, residing at Martinsburg, in the county of Berkeley and State of West Virginia, have invented certain new and useful Improvements in Rail Joints, of which the following is a specification, reference being had to the accompanying drawings.

10 This invention relates to a rail joint and has for an important object thereof the provision of a rail construction such that the joint is actually embodied in the rail. The strength and solidity of the joint are as great as the strength and solidity of the rail at any point in its structure.

A further object of the invention is to provide a structure of this character wherein at the meeting ends of the rail, a solid seat is provided for overlapped portions formed upon the rail ends, the rail ends each having a tongue overlapping the coacting rail ends and secured thereto so as to maintain the overlapped butt ends of the rail in properly assembled relation.

A further object of the invention is the provision of a device of this character which may be relatively cheaply produced, very durable and efficient in service and a general improvement in the art.

These and other objects I attain by the construction shown in the accompanying drawings, wherein for the purpose of illustration is shown a preferred embodiment of my invention and wherein:—

Figure 1 is a perspective view of a rail joint constructed in accordance with my invention;

Figure 2 is a perspective of one section 40 of the joint removed;

Figure 3 is a perspective of the other section of the joint removed;

Figure 4 is a perspective of a slightly modified rail joint;

Figure 5 is a perspective of one section 45 of the joint shown in Figure 4;

Figure 6 is a perspective of the other section of the joint shown in Figure 4;

Figure 7 is a perspective of the third and 50 slightly modified form of the rail joint; and

Figures 8 and 9 are sections on the line 8—8 and 9—9 of Figure 7.

Referring now more particularly to the drawings, each end of the rail has the web 55 10 thereof thickened between the head 11

and flange 12 so that it is but slightly of less thickness than the head, as indicated at 13. At one end of the rail, this thickened portion of the web and flange are cut away substantially midway the height of 60 the rail to produce a downwardly facing shoulder 14. At the opposite end of the rail, a complementary portion is cut away from the web and head, producing an upwardly facing shoulder or seat 15 for the reception 65 of the shoulder 14. Each rail is thus provided at one end with a projecting section 16 having the head and a portion of the enlarged web 13 and at its opposite end with a projection 17 having the flange and a portion 70 of the enlarged web 13.

Each end of the rail is provided upon its projecting portion 16 or 17 with a longitudinally extended key 16^a, 17^a, respectively, these keys being located at one side face 75 thereof with one side face of the thickened web portion 13 and are of less width than such thickened web portion, being preferably approximately one-third of the thickness of the web. The keys 16^a, 17^a, are arranged at opposite sides of the rail and the thickened web portion 13 inwardly of the ends of the notches producing the shoulders 14 and 15 are provided with recesses 17^b, 16^b receiving the corresponding tongues 17^a 80 or 16^a of an adjacent rail section. Each tongue 16^a, 17^a, has bolt openings 18 formed therein while the webs 13 have coacting openings 19 formed therein at the bases of the recesses 16^b and 17^b. The keys 16^a, 17^a 85 are preferably made so that they have a fairly loose fit in the recesses 16^b and 17^b so that when pressure is applied to one end of the rail section, it is transmitted to the other rail section not through the keys but 90 through the engagement of the shoulders 14 and 15. Since at this point of engagement, the width of the thickened web is approximately three times that of the ordinary web 10, it will be obvious that considerably greater support for the rail head 11 95 is provided at the joint than at any point in the rail. The thickness of the web sections at the recesses 16^b and 17^b is approximately twice that of the ordinary web and accordingly the rail is not weakened by the formation of these recesses. If desired, these recesses may be so formed that they open through both ends of the thickened portion 13 of the web, this construction per- 100

mitting more ready finishing of this portion of the rail as illustrated in Figures 4, 5 and 6.

While I have above referred to the tongues 5 16^a, 17^a as loosely fitting it will, of course, be understood that this last fitting refers only to the general engagement of the tongue in its recess. It will be obvious that the seat of the faces 14, 15 will hold the rails 10 against relative movement during the passage of a train in the general direction of the arrow of Figure 1. While a train passing in a direction opposite to this arrow would have a tendency to separate these 15 faces and this tendency must, of course, be overcome by the tongues. Accordingly, the upper face 16^c of the tongue 16^a and the lower face 17^c of the tongue 17^a have close engagement with the under surface of the 20 head of the rail and the upper surface of the flange 12 under all circumstances. So far as these faces 16^c and 17^c are concerned, the engagement will always be such as is shown in Figures 8 and 9. In the form of the 25 invention shown in Figure 7, the keys or tongues 16^a, 17^a have a relatively tight fit in their recesses and not only assist in preventing relative movement of the rails during the passage of the train in the last named 30 direction but likewise assist in preventing such movement during the passage of the train in the direction of the arrow of Figure 1. It will be obvious that by employing the thickened web construction, the rail web is 35 not weakened at any point in its length, and as a matter of fact, is of greater strength than the ordinary web employed at the end of the rail. A rigid support for the rail head is provided, preventing play at the 40 joint which rapidly results in destruction of the same. In applying the rails to the right-of-way, the rails are applied so that the direction of normal travel is in the direction of the arrow of Figure 1 and the ordinary 45 stress is taken up by the faces 15, 14 which, of course, offer greater resistance thereto. While I have, in each instance, illustrated the rail sections as secured together by means of ordinary bolts it will, of course, be 50 obvious that countersunk head bolts may be employed wherever it is found necessary or desirable.

Since the structures hereinbefore set forth are obviously capable of a certain range of 55 change and modification without departing from the spirit of my invention, I do not limit myself to such specific structures except as hereinafter claimed.

I claim:—

60 1. In a rail joint, a pair of abutting rail sections each having the web at the end of the rail thickened, one of said rail sections having a portion of the flange and the thickened portion of the web cut away to provide a downwardly facing shoulder, the

other of the rails having a portion of the head and the thickened portion cut away to provide an upwardly facing shoulder or seat for receiving the first named rail, said rails being each provided with a tongue overlapping a portion of the other of the rails and bolted thereto, each of said rails having in the side face of the thickened web portion thereof a recess loosely receiving the tongue of the other of the rails. 70 75

2. In a rail joint, a pair of abutting rail sections each having the web at the end of the rail thickened, one of said rail sections having a portion of the flange and the thickened portion of the web cut away to provide a downwardly facing shoulder, the other of the rails having a portion of the head and the thickened portion cut away to provide an upwardly facing shoulder or seat for receiving the first named rail, said rails being each provided with a tongue overlapping a portion of the other of the rails and bolted thereto, each of said rails having close engagement with an opposed face of the other of the rails at that side thereof, to prevent the movement of the sections of the joint, tending to separate said shoulders. 80 85 90

3. In a rail joint, a pair of abutting rail sections each having the web at the end of the rail thickened, one of said rail sections having a portion of the flange and the thickened portion of the web cut away to provide a downwardly facing shoulder, the other of the rails having a portion of the head and the thickened portion cut away to provide an upwardly facing shoulder or seat for receiving the first named rail, said rails being each provided with a tongue overlapping a portion of the other of the rails and bolted thereto, each of said rails having in the side face of the thickened web portion thereof a recess loosely receiving the tongue of the other of the rails, said tongues each having close engagement with an opposed face of the other of the rails at that side thereof to prevent the movement of the sections of the joint, tending to separate said shoulders. 100 105 110 115

4. In a rail joint, a pair of abutting rail sections each having the web at the end of the rail thickened, one of said rail sections having a portion of the flange and the thickened portion of the web cut away to provide a downwardly facing shoulder, the other of the rails having a portion of the head and the thickened portion cut away to provide an upwardly facing shoulder or seat for receiving the first named rail, said rails being each provided with a tongue overlapping a portion of the other of the rails and bolted thereto, each of said rails having in the side face of the thickened web portion thereof a recess loosely receiving the tongue of the other of the rails, the inner face of the recess 120 125 130

lying in the plane of the corresponding side of the rail web.

5. In a rail joint, a pair of abutting rail sections each having the web at the end of 5 the rail thickened, one of said rail sections having a portion of the flange and the thickened portion of the web cut away to provide a downwardly facing shoulder, the other of the rails having a portion of the head and 10 the thickened portion cut away to provide an upwardly facing shoulder or seat for receiving the first named rail, said rails being each provided with a tongue overlapping a portion of the other of the rails and bolted

thereto, each of said rails having in the side 15 face of the thickened web portion thereof a recess loosely receiving the tongue of the other of the rails, the inner face of the recess lying in the plane of the corresponding side of the rail web, said tongues each 20 having close engagement with an opposed face of the other of the rails at that side thereof to prevent the movement of the sections of the joint, tending to separate said shoulders. 25

In testimony whereof I hereunto affix my signature.

WILLIAM A. EVERSON.
